ABSTRACT: A stand presents two parallel rods set horizontal and in spaced relation one a little above and behind the other, which rods fit into opposite pairs of notches in opposite channel walls in the lower slender part of a thermoplastic shell whose upper part is shaped to fit into the toe portion of a shoe, and is in front of said rods at the notched region. There are a plurality of these shells spaced along said rods and serve as shoe trees. The upper part of these shells may be of shapes to hold other articles. Inside the said channel part and integral therewith, are cradles to support the rods, and strips extending out of the channel from along side the cradles, which while in plastic state, are bent to encircle said rods and form straps therefor. One of the rods has a series of spaced teats at the centerline positions of the shells. When a strip is bent as aforesaid, its associated teat acts as a die to draw a cup-form in the strap. The distal ends of the straps may be fused to the cradle body thereof.

INVENTOR,
John Bellock,

BY

ATTORNEY.

RACKS FOR SHOES AND OTHER ARTICLES

The present invention relates to racks for shoes and other articles, of the type comprising a frame or stand having horizontal rods or the like, which carry a plurality of shoe trees or similar supports in spaced relation therealong.

The principal object of this invention is to provide a novel and improved rack of the character described, in which shoe trees for instance are molded plastic shells having integral elements which cooperate with formations on the rod means whereby they are located in parallel relation and fixed in position. The junctures are hidden from view and do not involve the use of screws or rivets or other separate fastenings.

A further object thereof is to provide a novel and improved rack for shoes and the like, affording junction structure which takes advantage of the plastic's deformation and fusing qualities to assure secure assembly.

Still a further object is to provide a novel and improved rack for various articles, which are simple in construction, using a minimum of parts, are reasonable in their cost of manufacture, are easy to assemble to form a sturdy entity, and which are efficient for the purposes they are intended.

For one practice of this invention, the stand or frame presents two spaced parallel horizontal rods, one a little above and rearward of the other. Each shoe tree is a molded elongated shell of thermoplastic material having some resilient quality, comprising a bellied part to fit into the forward portion of a shoe, and a narrowed neck part extending downwardly and having opposite side walls, each wall provided with two spaced notches through which the rods extend. When the shoe is mounted on the shoe tree, its toe end is upward and its heel extends rearward; the entire shoe being behind the rods. Said neck part is a channel whose opening is rearward, and the bottom end of such channel may be closed.

Extending from inside said channel and integral therewith, there are two strip elements, each to one side of a rod-supporting cradle. These straps while hot, the shoe tree being on the rods, are bent over to make straps of them encircling said rods respectively. A teat or other protuberance struck from the material of one of the rods, acts as a die to draw a cup in the strap forced around it, and so the tree is held tightly on the rods.

In the accompanying drawing forming part of this specification, similar characters of reference indicate corresponding parts in all the views.

FIG. 1 is a perspective view of a shoe rack embodying the teachings of this invention.

FIG. 2 is an enlarged elevational view of one of the shoe trees in condition immediately before it is mounted on the rack frame or stand.

FIG. 3 is a top plan view of FIG. 2.

FIG. 4 is an enlarged perspective view of the shoe tree shown in the condition of FIG. 2.

FIG. 5 is an enlarged fragmentary perspective view of one of the rods on which the shoe trees are mounted; such rod being the one having the spaced teats.

FIG. 6 is a magnified fragmentary perspective view of a shoe tree of slightly modified construction.

FIG. 7 is a magnified section taken at line 7-7 in FIG. 3, showing the shoe tree set onto the mounting rods, ready for certain strip elements to be bent around said rods to serve as straps therefor.

FIG. 8 is a view like FIG. 7, showing the completed assembly, that is, the shoe tree is secured in place on its mounting rods.

In the drawing, the numeral 15 designates generally a shoe rack which includes a stand whose side members are spanned by one or more pairs of spaced, parallel horizontal rods, one rod 16 of each pair being a little above and behind the other rod 17. Each pair of rods have securely mounted thereon across them, a series of thermoplastic shells 18 which are in spaced relation along said mounting rods 16, 17, and serve as shoe trees.

In the embodiment illustrated, each shoe tree 18 is an elongated channel set across its mounting rods and extending upwardly therefrom; the longitudinal opening of the channel being towards the rear of the rack. That part of the channel which is above the mounting rods, is a belly-form of some resilient quality and of a shape to receive and fit into the toe part of the shoe, so when the shoe 20 is mounted, its heel 21 extends rearward. The belly-form 22 merges gracefully with a downwardly extending slender neck portion 23, whose lower end may be closed by a wall 24, connecting the side walls 25, 25' of said slender part. It is this slender part that crosses the mounting rods 16, 17, which are entered in notches in said side walls 25, 25'. Said notches in the wall 25 are denoted by the numerals 26 and 27, and in the wall 25', the notches are indicated as 26', 27'. The notches in each wall are directly opposite the corresponding notches in the other of said walls. Since all shoe trees 18 are identical, they will be in parallel relation, and of course they may be equi-spaced as shown along their mounting rods 16, 17, or in other spaced relation along said rods as design may prescribe.

Integral with the floor wall 19 of the channel and extending therefrom into the channel are the spaced cradles 28 and 29, which are for support of the rods 16 and 17 respectively; the cradle 28 being in alignment with the notches 26, 26', and the cradle 29 being in alignment with the notches 27, 27'. Also integral with the coat tree, there extends outwardly from the channel along one side of each of the cradles, are the strips 30 and 31; which are to be bent over while still hot out of the mould, to form the straps 30', 31' which tightly hold the shoe tree 18 in place on the rods 16, 17. A preferred means to lock each shoe tree in place against movement along the mounting rods 16, 17, is to have the rod 16 with struck up teats as 34 spaced therealong, at the center lines of the positions of said trees along said rods. Proper positioning of the shoe trees before bending the strips to strap form, may be accomplished by a jig at the assembly table, as would be the established practice in tool design and manufacturing procedure, and is well known as what would be a suitable production practice, that no further illustration thereof is believed necessary because same is readily understandable in the manufacturing arts and in engineering practice. It is evident that in bending said strips about the rod 16 centrally in relation to the teats 34, that each teat would act as a die and draw a cup as 35, into which it will project and remain to hold the shoe tree fixed against lateral movement. In bending the strip 30 around to form the strap 30', there may remain a space at 33, or there may be contact there at so the distal end of the strap is fused to the cradle 28, on the ledge 32.

The construction shown in FIG. 6 is identical to that shown in FIG. 4, except that the central portions of the cradles are omitted so as to leave the cavities 32 and 33, to save material. The cradles may be omitted if desired.

Although I have shown the employment of this invention in a shoe rack construction, it is evident that the upper part of the shells may be of suitable form to support hats, gloves and other articles desired to be held for storage or display, so being that this invention is capable of numerous forms and various applications without departing from the essential features herein disclosed, and its adaptations for other articles are believed readily understandable without the need for further illustration, it is therefore desired and intended that the embodiments shown and mentioned herein shall be deemed merely illustrative and not restrictive and that having shown and explained this invention,

I claim:

1. In a rack structure of the character described, a frame including two spaced parallel rods, one of which is provided with at least one teat extending laterally therefrom, one article-supporting member for each teat, including a channel of thermoplastic material extending across said rods; each of the opposite walls of said channel having two spaced notches commencing in the longitudinal edges of said walls, the notches in one wall being directly opposite the notches in the

other wall respectively; each of said rods being positioned through a pair of said opposite notches so that the teat is substantially centrally between said walls, and strips integral with the channel and extending therefrom interior said channel, between and spaced from said walls, the faces of each strip being across the channel; said strips being bent around each of the rods respectively while in plastic condition to form straps tightly encircling said rods respectively; said teat, acting as a die, causing a deformation in the strip thereat, whereby the teat is engaged in such deformation to secure said member against movement along the rods.

2. The rack structure as defined in claim 1, wherein said deformation is a cup-form.

3. The rack structure as defined in claim 1, including cradle structures within said channel and integral thereof, supporting

said rods respectively.

4. The rack structure as defined in claim 3, wherein the distal ends of the straps are fused to said cradles respectively.

5. The rack structure as defined in claim 1, wherein the distal ends of the straps are fused to the material of said channel.

6. The rack structure as defined in claimed 1, wherein the article-supporting member is an integral entity of thermoplastic material.

10 7. The rack structure as defined in claim 6, wherein the article-supporting member is a shell, whose channel portion is an elongated neck.

8. The rack structure as defined in claim 7, wherein the article-supporting member is a shoe tree.
